UNITED STATES PATENT OFFICE.

AGNES P. HANDLEY, OF OAKLAND, CALIFORNIA.

DESIGN FOR A DOLL.

61,158.

Specification for Design.

Patented July 4, 1922.

Application filed February 15, 1922. Serial No. 707. Term of patent 14 years.

To all whom it may concern:

Be it known that I, AGNES P. HANDLEY, a citizen of the United States, residing at Oakland, in the county of Alameda and State of California, have invented a new, original, and ornamental Design for Dolls, of which the following is a specification, reference being had to the accompanying drawing, forming part thereof.

The figure is a front view of a doll showing my new design.

I claim:

The ornamental design for a doll, as shown.

In testimony whereof I affix my signature.

AGNES P. HANDLEY.
